UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING UPON HEELS.

Application filed October 22, 1917, Serial No. 197,889. Renewed November 11, 1922. Serial No. 600,473.

To all whom it may concern:

Be it known that I, LOUIS A. CASGRAIN, a citizen of the United States, residing at Beverly, in the county of Essex and State 5 of Massachusetts, have invented certain Improvements in Machines for Operating upon Heels, of which the following description, in connection with the accompanying drawings, is a specification, like reference 10 characters on the drawings indicating like parts in the several figures.

This invention relates to machines for operating upon the heels of boots and shoes and particularly to machines for trimming 15 the breast portion of shoe heels, for example, Louis heels.

It has been usual to employ for this purpose a machine known as the Louis heel breast trimming machine similar to that described and claimed in United States Letters Patent No. 784,340, granted March 7, 1905, on application of Benjamin F. Mayo. In this machine the heel is held to a shoe support which engages the tread face of the heel 25 and the bottom of the forepart of the sole. The support is arranged for vertical movement parallel to the plane of operation of a cutter and is raised, to cause the cutter to trim the heel, by means of a foot treadle. The cutter then operates from side to side 30 of the heel to form a curved breast surface of cross groove which is straight transversely of the heel and shoe. The direction of the cut upon the portion of the heel next to the shank is, therefore, tangent to the curve of the shank and separate means has to be provided to trim the portion of the heel to the convex curve of the shank at each 35 side of the shank.

One object of the invention is to provide a machine which will trim the heel breast and also trim the portion next to the shank to the curve of the shank in a single operation.

Since in the use of the machine disclosed in the above-mentioned Letters Patent the shoe is raised by manual means, it is difficult and practically impossible so to manipulate the shoe that the cutter will com-

plete the cut without breaking away or 50 "spalling off" some of the material of the heel on the side where the cut is finished, due to the sudden ceasing of the resistance to upward movement when the cutter leaves the work. This effect is particularly noticeable when heels of leatherboard are being treated. While this objectionable effect has been remedied in the above-mentioned 55 foot power machine by mechanism described and claimed in United States Letters Patent No. 1,293,196, granted February 4, 1919, upon application of Daniel E. Quinlan, it is another object of this invention to provide a machine in which the support has its movement so timed and controlled by 60 power driven means that the cutter will effect a clean cut on the side edge where it leaves the heel.

Recently it has become usual to breast 70 Louis heels with the portions next the shank convex in transverse contour. A machine for this work is disclosed and claimed in United States Letters Patent No. 1,293,134, granted February 4, 1919, upon application of Thomas Lund. It is a further object of 75 the invention to provide an improved machine for this purpose.

In accordance with another object of this invention, the machine is organized to perform a plurality of operations such as those 80 mentioned, including convexing the portion of the breast next the shank, trimming the side portions of the heel to the contour of the shank, and also concaving the breast portion adjacent to the tread face all as 85 parts of a single operation and while the shoe is held upon a support or carrier, whereby a Louis heel breast may be completely formed in a single operation. The machine is preferably also so organized that all relative movements of the shoe and cutters which 90 require fatiguing effort on the part of the operator are performed by power.

A feature of the invention consists in the combination with a rotary cutter, of a shoe 95 support between which and the cutter there is provision for relative movement, and power means for moving the cutter and support

relatively to effect operation of the cutter upon the breast of the heel of a shoe on the support. The shoe support is preferably arranged for movement in two directions each 5 transverse to the direction of the axis of the cutter, and means responsive to manual movement of the shoe in one direction is provided to effect movement of the shoe by power in the other direction. As shown 10 herein, the shoe support has a to-and-fro movement and up-and-down movement, the up-and-down movements being effected automatically in response to the to-and-fro movements. That is, as the support is 15 moved inwardly toward the cutter and into its plane of operation, the support is automatically raised to carry the support and shoe into the field of operation of the cutter, and when the support is moved outwardly or 20 away from the cutter the support is automatically lowered to its original position.

Preferably the arrangement of the cutter and the shoe on the support is such that the 25 heel will be breasted by the cutter in a direction from side to side of the heel to form a cross groove in the breast face. As shown herein, the automatic movement of the work support is effected at a relatively low rate so that as the cutter and heel separate at the 30 lower side of the heel the cut is finished without breaking away or spalling off the material at the lower edge of the heel. It is desirable that the return of the work support to its original lowered or shoe receiving 35 position shall take place quickly. Accordingly, as a feature of the invention, the means for lowering the support is so constructed and arranged as to permit the support to be lowered or to drop by gravity 40 without necessarily waiting for the power means to lower it.

A further feature of the invention consists in a novel organization comprising a plurality of cutters, a shoe carrier, and 45 means for moving the carrier and cutters relatively first to effect operation of one of the cutters upon a shoe on the carrier and then to position the carrier and the other cutter for the operation of that cutter upon 50 the shoe by relative movement of the carrier and the said cutter. As shown herein, both cutters are rotary, one cutter having convex cutting edges shaped to correspond to the longitudinal curvature of the heel and the 55 other cutter straight cutting edges, the latter cutter being preferably frusto-conical and arranged above the breasting cutter. The shoe support, after being positioned in the plane of operation of the convex cutter, 60 is raised automatically for the operation of that cutter and stops opposite the upper frusto-conical cutter, the support being then movable at the will of the operator inwardly to cause the frusto-conical cutter to 65 form a concave portion in the breast of the

heel of the shoe on the carrier adjacent to the tread face of the heel, the support being then movable outwardly to cause automatic restoration of the support to lowered position. Means are also provided for preventing contact of the heel with the upper cutter during upward movement of the shoe until the center of the breast is opposite the axis of the cutter, for holding the support from movement in the direction of the axis of the cutter during movement of the support toward the cutter for concaving a heel, and for limiting the movement of the support toward the cutter to determine the depth of the concavity formed by the cutter. Of course, if it is not desired to perform the concaving operation upon the heel, the inward movement may be omitted and the support will be restored to normal position when moved outwardly while in its raised 85 position.

Another feature of the invention consists in means for effecting relative movement between the shoe and the breasting cutter while it is breasting the heel to cause it also to trim the portion of the heel breast next the shank to the transverse curve of the shank. To effect this the shoe support is arranged to permit movement thereof lengthwise of the cutter shaft and means shown as a cam guide, which preferably engages the shoe shank, is provided for guiding the shoe as the shoe support is raised to cause the cutter to follow the transverse curve of the shank and to trim 100 the portion of the heel next the shank in conformity to the lateral curve of the shank, the direction of movement effected by the cam guide being substantially in the direction of the cutter axis. In other words, 105 when related to the shoe in its normal position sole down the cutter and shoe support are arranged for relative traverse in a direction horizontally transverse to the shoe, and means is provided for controlling the 110 relative movement to compound with the relative movement of approach and separation between the cutter and the central point of the junction of the shank and heel breast which is normally produced by rectilinear 115 relative traverse, a component of relative separation and approach whereby the said central point and the cutter move relatively in a curve to make convex the junction of the shank and breast.

A further feature of the invention consists in improved means for effecting relative movement of the shoe support and cutter to cause the breast of the heel to be given a convex shape and this means is preferably 125 arranged to cooperate with the means for trimming the base portion of the heel or the upper forward end of the heel breast to the lateral curve of the shank so that the heel will be given a convex breast at that portion 130

below the shank considering the shoe in its normal position and at the portion adjacent to the shank will be trimmed to the lateral curve of the shank in the same operation.

- 5 As shown herein the cutting edge of the cutter is of approximate V-shape to enter the angle between the breast face of the heel and the shank, the formed cutting edge swinging around into approximate perpendicularity to the cutter axis, and two cams are provided arranged substantially at right angles to each other, one producing components of movement of the shoe perpendicular to the heel, and the other components of movement perpendicular to the shank to cause the breast to be curved about the vertical axis of the heel and about the longitudinal axis of the shoe or curved horizontally transverse to the shoe considering the shoe in its normal position sole down.
- 10 A further feature of the invention consists in novel positioning means for determining the lateral position of the forepart of the shoe upon the shoe support.
- 15 Another feature of the invention consists in novel clamping means for the shoe heel which not only effectively holds the heel from lateral movement during the operation of the first cutter, but positions the shoe heel centrally of the second cutter to receive the concaving cut on the portion of the breast near the top lift. The clamping means is arranged to engage the heel on opposite sides and is adapted to be operated
- 20 by one of the operator's hands while he holds the shoe with both hands upon the support or carrier.

These and other features of the invention will appear more fully from the following detailed description when read in connection with the accompanying drawings and will be pointed out in the appended claims.

In the drawings, Fig. 1 is a front view of a machine embodying this invention;

Fig. 2 is a side view of the upper portion of the machine;

Fig. 3 is a detail view of parts shown in Fig. 2;

Fig. 4 is a side view of the lower portion of the machine;

Fig. 5 is a plan view showing a shoe being operated upon by the lower rotary cutters with which the machine is equipped;

Fig. 6 is a similar view showing the shoe being operated upon by the upper rotary cutter; and

Fig. 7 is a perspective view of the mechanism for clamping the heel while being operated upon by the cutters.

Referring to Fig. 1 of the drawings, the numeral 2 indicates the column of the machine in which are bearings for a shaft 4 carrying tight and loose pulleys 6, 8, respectively, for the application of power to

the machine. The shaft 4 carries two other pulleys 10, 12, the smaller of which is belted to a suction fan 14 for drawing chips and dust away from rotary cutters 16, 18 which are driven from the other pulley 12. On the cutter shafts 20, 22 are pulleys 24, 26. A belt 28 connects the pulley 24 to the pulley 12 in the usual manner and another belt 30 is arranged outside of the belt 28 on the pulley 12 and extends over the pulley 26 to drive the rotary cutter 18.

The work support or carrier includes mechanism for assisting the operator in positioning and holding the work in proper orientation for the operation of the cutters which will now be described with reference to Figs. 2, 5, 6 and 7. The tread face of the heel is rested against a plate 40 which is normally below both of the cutters (Fig. 2). The forepart of the sole rests against a cylindrical spindle 42 which is mounted for rotation on a bracket 50. On the spindle are two series of pins 44, 46 spirally arranged, the pins of one series being opposite the corresponding pins of the other series. The first pin of one series is arranged nearest to the first pin of the other series and the second pin of one series a little farther distant from the corresponding pin of the other series and so on, so that by rotating the spindle a pair of pins may be selected suitably spaced to admit between them the sole of a shoe of the width to be operated upon by the machine. In Fig. 2 the pair of pins which is nearest together is shown in position to receive between them the sole of a shoe, the tread face of the heel of which is rested upon the plate 40. At the base of the spindle 42 is a bevel collar 48 having successive numbers co-operating with an index mark on the bracket 50 to indicate the proper setting of the spindle and pins for shoe soles of different widths, the spindle being held in a split clamp in the bracket 50 by a cap screw 51. The position of the shoe longitudinally of the cutter shaft is controlled by a plate 52 having a curved and beveled edge which engages the sole of the shoe in the shank, in a manner clearly shown in Figs. 5 and 6, and to be further described hereinafter.

To steady the shoe and hold the shoe heel, the tread face of which is being pressed against the plate 40, two pairs of clamps 60, 62 and 64, 66 are provided. The clamps 60, 62 engage opposite sides of the heel near the top lift. These clamps are on the ends of levers 68, 70 pivoted between their ends on pins 72, 74 supported on a member 76. The pairs of levers 68, 70 on their ends opposite the clamps 60, 62 have inclined faces which are engaged by co-operating faces 78, 79 (Figs. 6 and 7) formed on a U-shaped member 80 pivoted at 82 to the support 76. Obviously, movement of the member 80 to

ward the shoe will cause the faces 78, 79 to act upon the ends of the levers 68, 70 to separate them and cause the clamps 60, 62 to engage, and hold from sidewise movement, the heel at the sides near the tread face. The clamps 64, 66 similarly engage the sides of the heel nearer the heel seat face and rearwardly of the clamps 60, 62. The clamps 64, 66 are on levers 84, 86 mounted on the pivots 72, 74 and having their rear ends engaged by the ends of levers 88, 90 which have their ends connected by an integral sleeve portion 91 which is also pivoted on the pin 82. The levers 88, 90 are actuated by springs 92, 94 connecting them to the U-shaped member 80. It will be seen that the movement of the member 80 toward the heel will also actuate the levers 88, 90 through the springs 92, 94, causing them to separate the outer ends of the levers 84, 86 and move the clamps 64, 66 toward the heel and clamp it at points on its opposite sides near the seat face of the heel. The clamps 60, 62 are actuated directly and positively by the member 80 and the clamps 64, 66 are actuated yieldingly through the springs 92, 94. Each of the clamp levers is provided with an opening spring located in a slot 71 of the lever and acting on the pivot of the lever to swing the clamp open when permitted to do so by its closing mechanism. This U-shaped member 80 is arranged to be operated by pressure of the operator's right hand upon a handle portion 81, as indicated in Figs. 5 and 6. The support 76 upon which the clamps are mounted has a T-guide 93 which engages a T-slot 41 in the plate 40 (shown in Fig. 1 where the support 76 is removed) and permits movement of the support 76 relatively to the plate 40 longitudinally of the shoe. A screw 95 (Figs. 5 and 6) has a collar 96 engaging a recess in the plate 40 to hold the screw from longitudinal movement and has threaded engagement with the support 76 so that by rotation of a thumb head 98 on the screw the support 76 and the clamping means which it carries may be conveniently adjusted longitudinally of the shoe. The rear face of the heel rests against a surface 75 (Figs. 2 and 6) on the member 76 which constitutes an abutment to determine the longitudinal position of the shoe. This abutment is, of course, adjustable by the thumb head 98 to determine the amount of material to be removed from the heel by the cutter.

The plate 40 forms part of a member 100 which carries the bracket 50. The member 100 (Fig. 1) has a cylindrical portion 101 fitted in a split clamp in the upper end of a post 102. The split clamp is tightened by a screw 104. Conveniently to adjust the member 100 vertically when the clamp is loosened, a screw 106 is provided which is threaded into a clamp nut in the post 102

and has a capstan head 107 bearing against a lower face of the member 100. The post 102 is pivoted at 110 at its lower end (Fig. 4) for swinging movement to carry the work supporting and positioning devices 70 toward and from the machine in a direction somewhat inclined to the cutter shafts 20, 22. The extent of this movement is determined by a slot 111 in an arm 112 fastened at 114 to the machine frame. The pivot 110 extends through a block 115 which is pivoted by a stem 117 to the end of a lever 119. The stem 117 permits lateral play of the post 102 in the slot 111. This mounting, however, prevents rotation or twisting of the post 102 about its longitudinal axis. The post 102 is raised by mechanism to be described to carry the work first into operative relation to the lower cutter and then into operative relation to the upper cutter. 75 The path of upward movement of the work relatively to the cutters is determined partly by a templet 116 secured to the frame by screws 118 which pass through vertical slots in the templet. When the screws 118 are loosened the templet may be adjusted up and down by a screw 122 threaded into it and held from longitudinal movement by collars engaging above and below the arm 112. Co-operating with the contoured edge of the templet 116 is a roll 124 on a slide 126 which is mounted for horizontal movement in the upper end of the post 102 and is adjusted by means of a thumb head 128 on a screw threaded into the post 102 and having a collar 130 engaging a recess in the slide (Fig. 2).

The post 102, and hence the shoe, is raised slowly and positively by mechanism to be described. Obviously, the lower convexity 131 of the templet will act upon the roll 124 to determine the path of in and out movement of the shoe relatively to the lower cutter 16, the cut upon the heel starting upon the upper side of the heel with the shoe close to the cutter, the shoe being moved away from the cutter until the center of the heel breast is reached and then the shoe moving toward the cutter again until the cut is finished on the lower side of the heel. The breasting operation, therefore, takes place progressively from side to side of the heel, the longitudinal curvature of the heel breast being determined by the shape of the end and right-hand side of the 110 blades of the cutter 16 which are suitably formed, as shown, for that purpose. During this movement the shoe is held (as shown in Fig. 5) with the face of its shank in engagement with the guard 52 as is permitted by a lateral play of the post 102 in the slot 111 of the arm 112, the lower end of the post pivoting on the stem 117. The guard 52 acts as a guide, cam or templet 125 to determine the position of the shoe length- 130

wise of the cutter shaft and its edge where it engages the shoe shank is so contoured relatively to the contour of the templet 116 that, as the shoe is being guided out and in 5 by the templet 116, it will at the same time be guided to and fro longitudinally of the cutter shaft or transversely of the plane of movement of the cutter by the guide 52, and the cutter will be caused to trim the base 10 portion of the heel to the transverse curvature of the shank. During this operation guiding of the shoe is effected in such manner that the effective point of contact of the cutter and shoe is moved along the cutter 15 periphery as said point of contact moves from one side of the shoe to the other. Since the formed cutting edge of the cutter swings around into approximate perpendicularity to the cutter axis, the effective 20 operating point of contact of the cutter moves across the surface of revolution of the cutter as the said point of contact moves from one side of the shoe to the other in such manner that the junction of the heel 25 breast and shank is curved, the cam 52, with or without the cam 116 providing simple means for controlling the path of relative traverse of the shoe and cutter, which normally would be rectilinear, to compound 30 with such relative movement (which effects a relative movement of approach and separation between the cutter and the central point of the junction of the shank and heel breast) a component of successive relative 35 separation and approach so as to cause said central point and cutter to move relatively in a curve correspondingly to the desired convex curve at the junction of the shank and breast. Should the templet 116 be 40 made straight so as to effect the cutting of a straight cross groove in the heel breast, the guide 52 would be designed to effect the proper movement of the shoe so that the cutter would still trim the base portion 45 of the heel breast to the curve of the shank where the surface of the heel joins the surface of the shank.

As the shoe continues to rise, the roll 124 will engage the upper convexity 133 of the 50 templet 116 which moves the shoe outwardly to prevent engagement of the heel with the cutter 18 until the center of the heel breast is opposite the center of the cutter, whereupon the shoe stops. The roll 124 55 is now beyond the top of the templet and movement of the shoe toward the cutter is permitted. During the upward movement of the shoe, a pin 134, having a conical end portion and carried by a portion of the member 100 extending above the shoe, has 60 entered a slot 136 (Fig. 3) in a part 138 bolted to the top of the machine frame. As the conical end of the pin 134 enters the slot it centers the shoe laterally relatively 65 to the slot and the slot guides the shoe in its movement toward the cutter 18, the depth of cut being determined by a screw 140 with which the pin 134 contacts when the cut is completed. This cut is a concavity or scallop limited to the portion of 70 the breast adjacent to the top lift and is, of course, the shape of the cutter 18 and of such a depth as to extend substantially from corner to corner of the breast edge of the top lift. During this cutting operation the shoe and cutter are in the relation shown in Fig. 6. The plate 52 is preferably extended upwardly and shaped so as to constitute a guard for the cutter 18 as well as for the cutter 16. The plate 52 is 75 hinged to the frame by a pintle rod 144 (Fig. 2) so that it may be swung outwardly like a door for examination or change of the cutters 16, 18. The plate is held in closed position by a leaf spring 146 pushed under the pintle rod and bearing at one end against the frame and at the other end against the plate. The location of the shoe 80 engaging edge of the plate 52 relatively to the cutter is adjustably determined by a screw 147 (Fig. 1) threaded through the frame and engaging an upwardly extending lug 149 on the plate 52.

It is desirable to provide a guard to cover 85 the front of the upper cutter when not in use and to move the guard away from the cutter when the work approaches it. For this purpose a guard 148 having a curved flange extending across the front face of the cutter (Fig. 1) is pivoted at 150 to the plate 90 52 and a crank 152 on the pivot of the guard is connected by a flexible connection 154, for example, a cord, to a part of the machine which moves in a direction to apply tension 95 to the cord when the work approaches the cutter, thereby turning the crank and lifting the guard away from the front of the cutter and exposing it for operation upon the shoe heel. The cord 154 is connected 100 to a pin 155 on the lever 119 pivoted at 162 to the frame and carrying at its outer end the pivot 110 of the post 102. The movement of the lever 119 at the point of attachment of the cord 154 is more than that required for the 105 crank to lift the guard. The cord is, therefore, given a certain amount of slack to allow the lever to raise the work for the operation of the lower cutter while the guard of the upper cutter remains in guarding position, the slack being taken up and the guard raised as the shoe is raised further for the 110 operation of the upper cutter. To take up the slack of the cord and keep it straight 115 at all times, a light coiled spring 164 is provided connected between the pin 155 and a point on the cord such that in the position of Fig. 4 little or no tension will be put upon the cord. The slack of the cord is 120 preferably arranged inside the coiled spring. 125

130

The tension of the spring is in itself insufficient to raise the guard and when the slack within the spring is taken up the guard is positively raised by the pull on the 5 cord 154.

The weight of the post 102 and connected parts is preferably partially counterbalanced by a heavy tension spring 172 connected between the outer end of the lever 119 and a stationary portion of the machine shown as the member 112.

shown as the member 112.

Means is provided for operating the lever 119 automatically to raise the shoe for the operation of the two cutters in succession and lowering it after the cutting operations, the automatic movements being preferably controlled by movement of the work support, for example, the post 102, toward and from the machine. The rear end of the lever 119 is bifurcated to receive one end of a link 178 pivoted to the lever by a pin 180. The opposite end of the link 178 is on a crank pin 182 of a crank 184 on a shaft 186. Suitable speed reducing gearing is provided between the shaft 4 and the shaft 186. As shown, this comprises a worm 188 on the shaft 4 meshing with a worm wheel 189 on a vertical shaft 190 having at its upper end a worm 191 meshing with a worm wheel 192 on the shaft 186. The worm wheel 192, therefore, is continuously driven at a slow speed when the machine is in operation. Between the worm wheel 192 and the crank 184 clutch mechanism is provided by which the crank 184 is moved 180° and stopped. A clutch disk 194 has a single knock-off projection 196 which co-operates with either of two stop arms 198, 200 to throw out the clutch. The stop 198 is pivoted at 202 to a stationary support and the arm 200 is similarly pivoted at 204, the arms being held toward each other and against the disk 194 by a spring 206. On each of the stop arms is a projection 208 and between them is a swinging link 210 pivoted at 211 to the frame and arranged when swung to contact with one or the other projection 208 and to push one or the other stop arm out of engagement with the knock-off projection 196 to start the machine. A link 212 connects the link 210 with the post 102. When the post is swung in toward the machine and the link 210 swung against the projection 208 on the arm 198 that arm is pushed out of engagement with the knock-off projection 196 (as shown in Fig. 4), allowing the clutch to go in and the crank 184 to revolve and through the link 178 to operate the lever 119 to raise the post 102

60 operate the lever 119 to raise the post 102 and the shoe supporting and positioning means. When the shoe is completely raised in position to be moved inwardly of the machine for the operation of the cutter 184 upon the heel, the knock-off projection 196 engages the stop on the arm 200 and ver-

tical movement of the shoe ceases. After the operation of the cutter 18 the shoe and post 102 are moved outwardly, the pull on the link 212 moving the arm 200 out of stopping position and allowing the crank 184 to move through another 180° to its original position where it stops with the shoe lowered. 70

In the operation of the machine a shoe is grasped by the operator with both hands and positioned with the tread face of the heel against the plate 40 and with the rear end of the heel adjacent to the top lift abutting against the surface 75 of the member 76. The bottom of the forepart of the sole is held against the spindle 42 which has been rotated to bring into position a pair of pins 46, the pins of which are so spaced as to hold the forepart of the shoe against lateral movement. The operator now presses upon the lever 81 with his right hand which still grasps the heel end of the shoe. The shoe is now definitely positioned relatively to the shoe support or carrier and held in position thereon. Next by pressing upon the shoe the carrier is swung on the pivot 110 toward the machine, the connection 212 causing the clutch to be tripped to start the machine, whereupon the support and shoe begin to ascend. As the heel passes the cutter 16 the support is moved out and in by the action of the cam or templet 116 upon the roll 124 and a convex form given to the portion of the heel breast which lies transverse to the plane of rotation of the cutter (Fig. 6) while the longitudinal curvature of the breast is determined by the contoured edge or form of the cutter 16. During this movement the support has been pressed inwardly to maintain the roll 124 in contact with the templet 116 and has been pressed sidewise toward the right to hold the shank of the shoe sole in contact with the contoured edge of the plate 52. This edge acts as another cam or templet to control movement of the shoe in a direction substantially perpendicular to the shank portion and to the breast face of the heel or lengthwise of the cutter axis and causes the cutter to follow the transverse contour of the shank and to trim the base portion of the heel in conformity with the curve of the shank. The movement of the shoe past the cutter being gradual and controlled at all times by power, the heel as it leaves the cutter is given a clean edge without any of the material of the heel being broken away as often occurs with foot power machines.

The support continues to rise and is pushed outwardly again by engagement of the roll 124 with the upper portion 133 of the templet 116 to avoid danger of contact of the shoe with the upper cutter 18. The cutter shield 148 is raised by tension on the 130

cord 154 and the stud 134 enters the slot 136 which prevents lateral play of the support and guides it for presentation of the tread portion of the heel breast to the cutter 18 (Fig. 3). The support now stops in its upper position and is swung in toward the cutter as far as permitted by the abutment screw 140 which limits the depth of cut. After this operation the support is 5 swung outwardly, causing the clutch to be again tripped whereupon the support begins to descend. The operator may, however, lower the support ahead of the power mechanism, once it has started, so that the 10 crank 184 is beyond dead center, and so gain time for removal of one shoe and positioning of another on the support. Whether the support has to be pushed down or drops by 15 gravity depends upon the tension of the spring 172 and both arrangements are contemplated as within the invention. The descent of the support ahead of its power actuation is, of course, permitted by the usual 20 one-way ball or roller clutch forming a part 25 of the usual clutch of the Horton type.

Having fully described my invention, what I claim as new and desire to secure by United States Letters Patent is:

In a machine of the class described, the 30 combination of a rotary cutter, shoe supporting means for holding a shoe and its attached heel in predetermined position, and power means for effecting relative operative movement of the cutter and shoe supporting 35 means to cause the cutter to breast the heel.

2. In a machine of the class described, the combination of rotary breasting means, shoe supporting means for holding a shoe and its attached heel in predetermined position, 40 and power operated means for effecting operative movement of the shoe past the breasting means to effect breasting of the heel.

3. In a machine of the class described, the 45 combination of heel breasting means, shoe supporting means, and power means rendered effective by inward pressure of the shoe upon the supporting means for effecting relative movement of said means and 50 the breasting means to cause the shoe heel to be breasted.

4. In a machine of the class described, the combination of rotary heel breasting means, means for locating the shoe relatively to the breasting means so that relative movement of the breasting means and locating means will cause the heel to be breasted, and means responsive to pressure of the shoe upon the locating means to effect 55 relative movement of the locating means and the breasting means.

5. In a machine of the class described, the combination of rotary heel breasting means, heel holding means, power means 60 for relatively actuating the breasting means

and the holding means to effect breasting of the heel, and means responsive to movement of the holding means for setting the power means in operation.

6. In a machine of the class described, the 70 combination of rotary heel breasting means, heel holding means, power means for relatively actuating the breasting means and the holding means to effect breasting of the heel, and means responsive to movement of the 75 holding means effected by pressure of the heel inwardly toward the breasting means for setting the power means in operation.

7. In a machine of the class described, the 80 combination of heel breasting means, shoe positioning means, power means for effecting relative movement of the breasting means and the shoe positioning means to cause the heel of a shoe in the positioning means to be 85 breasted in a direction from side to side of the heel, and means responsive to movement of the positioning means for setting the power means in operation.

8. In a machine of the class described, the 90 combination of heel breasting means, shoe positioning means, power means for effecting relative movement of the breasting means and the shoe positioning means to cause the heel of a shoe in the positioning means to be 95 breasted in a direction from side to side of the heel, and means responsive to movement of the positioning means effected by pressure of the shoe for setting the power means in operation.

9. In a machine of the class described, a 100 rotary cutter, a shoe support, means engaging the sides of the heel for clamping the heel of a shoe upon the support, and means for effecting relative movement of the cutter and support to cause the heel to be breasted 105 progressively from side to side of the heel.

10. In a machine of the class described, a 110 rotary cutter, a shoe support, means for clamping a heel upon the support, and power means rendered operative by movement of the support toward the cutter for effecting relative movement of the cutter and support to cause the heel to be breasted progressively from side to side of the heel.

11. In a machine of the class described, the 115 combination of heel breasting means, shoe positioning means, power means for effecting relative movement of the breasting means and the shoe positioning means to cause the heel of the shoe in the positioning means to be breasted, means responsive to movement of the positioning means in one direction for setting the power means in operation, and means responsive to movement of the positioning means in another direction to permit the positioning means to drop by gravity. 120

12. In a machine of the class described, the 125 combination of heel breasting means, shoe positioning means, power means for effecting relative movement of the breasting means 130

- and the shoe positioning means to cause the heel of a shoe in the positioning means to be breasted, means responsive to movement of the positioning means in one direction for setting the power means in operation, and means responsive to movement of the positioning means in another direction for effecting descent of the positioning means by power.
10. 13. In a machine of the class described, the combination of heel breasting means, shoe positioning means, power means for effecting relative movement of the breasting means and the shoe positioning means to cause the heel of a shoe in the positioning means to be breasted, means responsive to movement of the positioning means in one direction for setting the power means in operation, means responsive to movement of the positioning means in another direction for effecting descent of the positioning means by power, and means permitting the positioning means to descend ahead of the power means for effecting its descent.
15. 14. In a heel breasting machine, a plurality of cutters, a shoe support, and means for moving the shoe support past one cutter for the operation of that cutter upon the heel breast and into position for operation of the other cutter upon the heel breast.
20. 15. In a heel breasting machine, a plurality of cutters, a shoe support, and means for moving the shoe support past one cutter for the operation of that cutter upon one portion of the heel breast and maintaining the support in position for operation of the other cutter upon another portion of the heel breast.
25. 16. In a heel breasting machine, a rotary cutter, a shoe support, means for moving relatively the cutter and support to effect operation of the cutter upon the heel of a shoe on the support to breast the heel progressively from side to side of the heel, and a secondary cutter constructed and arranged relatively to the first cutter to be in position for operation upon the heel after the operation of the first cutter upon the heel.
30. 17. In a heel breasting machine, a rotary cutter, a shoe support, means for moving the support past the cutter to cause the cutter to trim the breast of a heel on the support, and a second cutter arranged in position for operation on the heel after the support has passed the first cutter.
35. 18. In a machine of the class described, a plurality of cutters each adapted for operation upon the breast of a heel, a shoe support, and means for moving the shoe support first to a position for operation of one cutter upon the heel breast and then into position for operation of the other cutter upon the heel breast upon relative movement of the support and said other cutter.
40. 19. In a machine of the class described, a plurality of cutters each adapted for rotation to breast a heel, a carrier, and means for moving the carrier first past one of the cutters for the heel to be treated by that cutter and then into position for treatment by the other cutter when the carrier is moved in another direction.
45. 20. In a machine of the class described, a breasting cutter adapted to form a cross groove in a heel breast, a shoe support, means for moving relatively the cutter and support to effect cross grooving of the breast, a rotary concaving cutter, and means permitting relative movement of the support and concaving cutter to form a concave face in the heel breast adjacent to the top lift.
50. 21. In a machine of the class described, a rotary breasting cutter adapted to cut a cross groove in a heel breast, shoe supporting means, means for moving relatively the cutter and support to effect cross grooving of the breast, a concaving cutter, and means permitting relative movement of the concaving cutter and the support to form a concave face in the heel breast adjacent to the top lift.
55. 22. In a machine for breasting Louis heels, a rotary cutter, a shoe support, and means constructed and arranged to effect relative movement of the cutter and support progressively past each other such that a relatively straight Louis breast will be formed on the heel and the portion of the heel extending along the shank will be shaped to the curve of the shank.
60. 23. In a machine for breasting Louis heels, a rotary cutter, a shoe support, means for relatively moving the support and cutter to effect relatively straight cross grooving of the breast of the heel of a shoe on the support, and means for moving the shoe and cutter relatively to cause the cutter to shape the forwardly extending base portion of the heel to the curve of the shank transversely of the shoe.
65. 24. In a machine of the class described, the combination of a rotary cutter, a shoe support, the cutter and support being relatively movable to bring the shoe into the plane of operation of the cutter, and means responsive to such relative movement for then relatively moving the support and cutter automatically to effect operation of the cutter upon the shoe.
70. 25. In a machine of the class described, the combination of a rotary cutter and a shoe support relatively movable first to bring the shoe into the plane of operation of the cutter, the cutter and support being then relatively movable to effect operation of the cutter upon the shoe, and means responsive to the first relative movement to cause the second relative movement to be effected.
75. 26. A heel breasting machine having, in combination, a rotary cutter having a cutting face of substantial width, a shoe sup-

port, means for effecting and controlling relative movement of said cutter and said shoe support arranged to cause successive portions of the heel breast from side to side of the heel to be brought successively into contact with the cutter, and means for controlling relative movement of the shoe and cutter in a direction parallel to the cutter axis to cause the cutter to follow the transverse 10 curve of the shank.

27. A heel breasting machine having, in combination, a rotary cutter having a cutting face of substantial width, a shoe support, means for relatively moving the cutter and 15 shoe tangential of the cutter, and means for simultaneously moving the shoe transversely of the plane of rotation of the cutter to cause the cutter to trim the base of the heel to the transverse curve of the shank.

28. In a machine of the class described, the combination of a cutter, a shoe support, means for moving the cutter and support relatively to cause the cutter to operate upon 25 a shoe heel from side to side of the heel, means responsive to manual movement of the support for causing said relative movement to take place automatically, and means responsive to manual movement of the support in another direction to cause restoration of 30 the support to its original position.

29. In a machine of the class described, the combination of a cutter, a shoe support, means for moving the cutter and support relatively to cause the cutter to operate upon a 35 shoe heel from side to side of the heel, means responsive to manual movement of the support toward the cutter for causing said relative movement to take place automatically, and means responsive to manual movement 40 of the support away from the cutter to cause restoration of the support to its original position.

30. In a machine of the class described, the combination of a cutter arranged for rotation 45 in a vertical plane, shoe positioning means to which a shoe is held by the hands of the operator, said means being movable with the shoe to bring a portion of the heel into position when raised to be acted upon by the 50 cutter from side to side of the heel, and means becoming effective in response to said movement of the positioning means to cause said means to be raised and the heel to be acted upon by the cutter.

31. In a machine of the class described, the combination of a cutter arranged for rotation in a vertical plane, a shoe carrier to which a shoe is held by the hands of the operator, the carrier being movable with the 60 shoe to bring the breast portion of the heel into such a position that when raised it will be acted upon by the cutter to breast the heel from side to side of the heel, and means becoming effective in response to movement 65 of the carrier toward the cutter to cause the

shoe carrier to be raised and the heel to be breasted.

32. In a machine of the class described, the combination of a rotary cutter mounted on a horizontal axis, a shoe support pivoted for movement vertically and movable from and toward the cutter, means for raising the support by power, and means for guiding the support from and toward the cutter as it is raised to cause the cutter to form a convex face upon the portion of the shoe acted upon by the cutter. 70

33. In a machine of the class described, the combination of a rotary cutter mounted on a horizontal axis, a shoe support movable vertically and movable toward and from the cutter, mechanism for raising the support by power, and means for controlling the movement of the support toward and from the cutter as it is raised in such manner that the breast face of the heel is formed and the base of the heel is shaped to correspond to the curve of the shank. 80

34. In a machine of the class described, the combination of a rotary cutter, a shoe support movable to carry a shoe across the cutter to cause the cutter to breast the heel, means rendered effective by movement of the support toward the cutter to cause the support to be carried across the cutter and to stop with the shoe raised, and means rendered effective by reverse movement of the shoe support for returning the support to initial position. 90

35. In a machine of the class described, the combination of a rotary cutter, a shoe support movable to carry a shoe across the cutter to cause the cutter to breast the heel from side to side of the heel and also movable toward and from the cutter, means responsive to movement of the support toward the cutter to cause the support to be carried automatically across the cutter to be guided from and toward the cutter and to be stopped with the shoe raised, and means responsive to reverse movement of the shoe support which permits return of the support to its lowered position at a higher rate than the rate at which it is raised. 100

36. In a machine of the class described, the combination of a rotary cutter, a shoe support movable to carry the shoe across the cutter to cause the cutter to breast the heel and also movable substantially perpendicularly to the shank of a shoe on the support, means for moving the support to carry the shoe across the cutter, and means for guiding the shoe longitudinally during its movement across the cutter to cause the cutter to follow the curve of the shank. 110

37. In a machine of the class described, the combination of a rotary cutter, a shoe support movable to carry the shoe across the cutter to cause the cutter to breast the heel and also movable toward and from the cut- 120

ter, power means responsive to movement of the support toward the cutter to cause the support to be moved across the cutter, means acting to guide the shoe from and toward 5 the cutter during its movement across the cutter to cause the cutter to follow the curve of the shank, and self-acting means for holding the support in raised position.

38. In a machine of the class described, the 10 combination of a rotary cutter having portions of its cutting edge disposed transversely of its plane of rotation, a shoe support between which and the cutter there is relative movement to cause the cutter to 15 breast the heel, the support and cutter being also relatively movable transversely of the plane of movement of the cutter, means for effecting relative movement of the support and cutter to cause the cutter to breast the 20 heel, and means for determining relative movement of the shoe and cutter transversely of the cutter during the breasting operation to cause the cutter to follow the curve of the shank.

39. In a machine of the class described, the 25 combination of a rotary cutter, a shoe support movable to carry the shoe across the cutter to cause the cutter to breast the heel and also movable toward and from the cutter, means responsive to manual movement 30 of the support toward the cutter to cause the support to be moved across the cutter, means for guiding the shoe from and toward the cutter during movement of the shoe across the cutter to cause the cutter to 35 follow the curve of the shank, automatic means for stopping the support in raised position, and means responsive to the manual movement of the shoe support away from the cutter to return the support to its initial 40 position.

40. In a machine of the class described, the 45 combination of a rotary cutter mounted on a horizontal shaft and having a transversely curved cutting face of substantial extent, a shoe support movable toward and from the cutter and also normally to the breast of the heel of a shoe carried by the support, a guide adapted to engage the shoe 50 shank, and means for raising the shoe to carry it across the cutter, said guide controlling movement of the shoe normally of the heel breast and relatively to the cutter to cause the breast to be trimmed to the curve 55 of the shank.

41. In a machine of the class described, the 60 combination of a rotary cutter mounted on a horizontal shaft, a shoe support movable toward and from the cutter about an axis arranged at an acute angle to the direction of the cutter shaft and also mounted for vertical movement, a guard adapted to engage the shoe shank to determine the position of the shoe longitudinally with respect

to the cutter, means for raising the shoe to 65 carry it across the cutter, and means for controlling movement of the shoe relatively to the cutter in said angular direction to cause the breast to be trimmed to the curve of the shank. 70

42. In a machine of the class described, the combination of a rotary cutter, a shoe carrier movable across the cutter, a plate on 75 said carrier to receive the tread face of the heel, clamping means arranged to engage the sides of the heel, and means for operating the clamp to hold the heel.

43. In a machine of the class described, the combination of a rotary cutter, a shoe support movable across the cutter, a plate 80 on said support to receive the tread face of the heel, clamping means mounted on the plate and arranged to engage the sides of the heel, and means adjacent to the operator's hand which holds the rear end of the shoe 85 for operating the clamp to hold the heel.

44. In a machine of the class described, the combination of a rotary cutter, a shoe support movable across the cutter, a plate on 90 said support to receive the tread face of the heel, clamping means engaging the sides of the heel near the tread face, and means for positively operating the clamping means to hold the shoe. 95

45. In a machine of the class described, the combination of a rotary cutter, a shoe support movable across the cutter and to which the shoe is held, a plate on said support to receive the tread face of the heel, clamping means for engaging the heel, and 100 means for positively operating the clamping means to hold the heel arranged for convenient operation by a hand which also holds the shoe.

46. In a machine of the class described, the combination of a rotary cutter, shoe 105 positioning means movable across the cutter and adapted to receive the tread face of the heel held in the operator's hands, clamping means for engaging opposite sides of the heel near the tread face of the heel, clamping 110 means for engaging opposite sides of the heel near the heel seat, and means adjacent to a hand of the operator which holds the shoe against the positioning means for operating the tread clamps positively and for operating the seat clamps yieldingly to hold the heel from lateral movement. 115

47. In a machine of the class described, the combination of a rotary cutter, a shoe support movable across the cutter, a plate 120 on said support to receive the tread face of the heel, clamping means for engaging opposite sides of the heel near the tread face of the heel, clamping means for engaging 125 opposite sides of the heel near the heel seat, and means adjacent to the operator's hand which holds the heel portion of the shoe

against the plate for operating the tread clamps positively and for operating the seat clamps yieldingly, said clamps operating to hold the heel from lateral movement during 5 operation of the cutter.

48. In a machine of the class described, the combination of a rotary cutter, a shoe support movable across the cutter, means on the support for positioning and holding the 10 heel of the shoe, and forepart positioning means comprising a rest for the bottom of the forepart, and a series of pairs of differently spaced pins so constructed and arranged that any pair of pins may be brought into 15 position to hold the forepart of the shoe from lateral movement.

49. In a machine of the class described, the combination of a rotary cutter, a shoe support movable across the cutter, means 20 on the support for positioning and holding the heel of the shoe, and forepart positioning means comprising a post against which the bottom of the forepart is rested, and a series of pairs of differently spaced pins on 25 the post, the post being arranged for rotation to bring any pair of pins into position to hold the forepart of the shoe from lateral movement.

50. In a machine of the class described, 30 the combination of a rotary cutter, a shoe support movable across the cutter, means on the support for positioning and holding the heel of the shoe, and forepart positioning means comprising a series of pairs of differently spaced pins on the forepart rest, said 35 rest being movable to bring any pair of pins into position to hold from lateral movement the forepart of the shoe.

51. In a machine of the class described, 40 the combination of a rotary cutter, a shoe support movable across the cutter, means on the support against which the heel of the shoe may be rested, a rotatable forepart rest, and a series of pairs of differently 45 spaced pins on the forepart rest, the operator being able by rotating the rest to bring any pair of pins into position to hold from lateral movement the forepart of a shoe of any width.

50. 52. In a machine of the class described, 50 the combination of two rotary cutters arranged on horizontal shafts one over the other, a shoe support, and means for moving the shoe support and cutters relatively 55 to bring a shoe on the support first into operative relation to one cutter and then into position for operation of the other cutter upon it.

53. In a machine of the class described, 60 the combination of two rotary cutters, a shoe support, and means for automatically and uninterruptedly moving the shoe support and cutters relatively to carry a shoe on the support first past one cutter to cause,

operation of that cutter to be effected, then 65 into position for operation of the other cutter upon the shoe, and then arresting said relative movement.

54. In a machine of the class described, 70 the combination of two rotary cutters, and power operated shoe carrying means for moving the shoe uninterruptedly past one of the cutters and holding the shoe in that position until operated upon by the other cutter. 75

55. In a machine of the class described, the combination of two rotary cutters, a shoe support, automatic means for raising the shoe support past one of the cutters and holding the shoe support in that position 80 until operated upon by the other cutter, and automatic means responsive to movement of the support away from the second cutter for lowering the shoe support.

56. In a machine of the class described, 85 the combination of two rotary cutters, power operated shoe carrying means for moving the shoe past one of the cutters and arresting movement of the carrier until the shoe is operated upon by the other cutter, and means 90 responsive to movement of the carrying means away from the said cutter to restore the carrying means to initial position.

57. In a machine of the class described, 95 the combination of two rotary cutters, a shoe carrier, and automatic means for raising the carrier past one of the cutters and stopping it in raised position for operation of the other cutter upon the shoe, and means responsive to movement of the shoe carrier 100 away from the cutter to lower the carrier.

58. In a machine for breasting Louis heels, 105 the combination of a single cutting means for convexing the shank portion of the heel breast and for breasting other portions of the breast laterally straight, a heel support, means for effecting relative movement between the cutting means and the heel to effect relative traverse of the cutting means and heel, and means for simultaneously effecting relative movement of the cutting means and heel in a direction substantially perpendicular to the breast face of the heel to cause the cutting means to convex the shank portion of the heel. 110

59. In a machine of the class described, 115 the combination of means for convexing the shank portion of a heel breast, means for concaving the tread portion of the breast, and a heel support between which and the said means there is provision for relative movement to cause the said means to operate successively upon the heel. 120

60. In a machine of the class described, 125 the combination of a plurality of rotary cutters, a shoe support movable to bring the shoe into operative relation to the cutters in succession, means for controlling the move-

- ment of the shoe relatively to one cutter, and a guide having a slot perpendicular to the axis of the second cutter to control movement of the shoe relatively to said cutter.
- 5 61. In a machine of the class described, the combination of a rotary cutter having a convex cutting face, a frusto-conical cutter, a shoe support movable to bring the shoe into operative relation to the cutters in succession, means for controlling the movement of the shoe relatively to the convex cutter to form a convex portion on the heel near the shank, and a member having a slot inclined to the edge of the frusto-conical cutter to control movement of the shoe relatively to said cutter to form a concave portion near the tread face of the heel. 70
- 10 62. In a machine for operating upon the heels of boots and shoes, the combination of a breasting knife and a concavaging knife, and a work carrier arranged for movement to carry the work first into operative relation to one of said knives and then into operative relation to the other knife. 80
- 15 63. In a machine for operating upon the heels of boots and shoes, the combination of a breasting knife and a concavaging knife, and a work carrier arranged for movement to carry the work first into operative relation to the breasting knife and then into operative relation to the concavaging knife. 85
- 20 64. In a machine for operating upon the heels of boots and shoes, the combination of a breasting knife and a concavaging knife, a work carrier arranged for movement to carry the work first into operative relation to one of said knives and then into operative relation to the other knife, and automatic means for moving the carrier past one of the knives and stopping the carrier opposite the other knife. 90
- 25 65. In a machine for operating upon the heels of boots and shoes, the combination of a breasting knife and a concavaging knife, a work carrier arranged for movement to carry the work first into operative relation to the breasting knife and then into operative relation to the concavaging knife, means for moving the carrier past one of the knives and stopping the carrier opposite the other knife, and means for guiding the carrier for movement toward the concavaging knife. 95
- 30 66. In a machine for operating upon the heels of boots and shoes, the combination of a breasting knife and a concavaging knife, a work carrier arranged for movement to carry the work first into operative relation to the breasting knife and then into operative relation to the concavaging knife, means for moving the carrier past one of the knives and stopping the carrier opposite the other knife, means for guiding the carrier for movement toward the concavaging knife, and adjustable means for arresting the action 100
- 35 67. In a machine for operating upon the heels of boots and shoes, the combination of a rotary breasting cutter, a shoe carrier constructed and arranged to receive and position a shoe held in the operator's hands, and means operating at a substantially constant rate for giving the carrier a continuous steady movement to carry the shoe heel past the cutter and insuring that the cut will be finished without tearing the stock as the cutter leaves the heel. 105
- 40 68. In a machine for operating upon the heels of boots and shoes, the combination of a rotary breasting cutter, a shoe carrier constructed and arranged to receive and position a shoe held in the operator's hands, and means for giving the carrier a continuous steady movement past the cutter to insure that the cut will be finished without tearing the stock as the cutter leaves the heel. 110
- 45 69. In a machine of the class described, a plurality of cutters, a work support movable from one cutter to the other, a shield for one of the cutters in shielding position when the support is opposite the other cutter, and means for moving the shield away from the shielded cutter when the work support approaches it. 115
- 50 70. In a machine of the class described, the combination with a rotary cutter and a rest for a shoe constructed and arranged to position the shoe with the longitudinal median plane of the shoe parallel to the axis of the cutter and for movement across the acting face of the cutter, of means for moving the shoe rest to cause the cutter to follow the transverse curve of the shoe shank, and means acting during said movement to move the rest toward and from the cutter to form a laterally curved breast face upon the heel. 120
- 55 71. In a machine of the class described, the combination of a rotary cutter, means for presenting a shoe to the cutter, and means for effecting relative movement of the cutter and shoe presenting means to cause the cutter to trim the shank end of the heel breast from side to side in a path parallel to the curve of the shank of the shoe. 125
- 60 72. A heel breasting machine having, in combination, means for supporting the tread face of the heel of a shoe, a rotary cutter arranged with its axis intersecting the plane of said tread face, means for effecting relative movement of the cutter and supporting means to cause the heel to be breasted, and means acting as an incident to said relative movement to effect relative movement of the shoe and cutter in a direction substantially parallel to the cutter axis and cause the cutter to follow the curve of the shank. 130
- 65 73. In a machine of the class described, the combination of a rotary cutter, a shoe

support, power means for effecting relative operative movement of the cutter and support to cause the heel of a shoe on the support to be breasted, and means for causing a reverse relative movement of the cutter and support to normal position at a higher rate than the rate at which the operative movement is effected.

74. In a machine for breasting Louis heels, 10 a rotary cutter, a shoe support, and means comprising two cams substantially at right angles to each other for giving the shoe support simultaneous movements relative to the cutter about centers below the shoe sole.

15 75. In a machine for breasting Louis heels, a rotary cutter, and a shoe support constructed and arranged to move past each other in a path having components lying in planes respectively perpendicular to the heel and shank, whereby the breast of the heel is curved about the vertical axis of the heel and the longitudinal axis of the shoe.

20 76. In a machine for breasting Louis heels, a rotary cutter having a formed cutting edge of approximate V-shape, the longitudinal axis of the V being perpendicular to the axis of the cutter, a shoe support constructed and arranged to support a shoe with its sole facing the cutter and to move 25 past the cutter, and two cams arranged to produce relative movements of the support and cutter substantially parallel and perpendicular respectively to the cutter axis to give the breast of the heel a compound 30 curvature about two axes, one lying in the direction of the vertical axis of the heel and the other lying in the direction of the length of the shoe.

35 77. In a machine for breasting Louis heels, 40 a rotary cutter, a work support constructed and arranged to present the lower surface of a shoe to the cutter with the angle between the heel breast and the shank toward the cutter, and means for moving 45 the work support comprising guides in planes respectively perpendicular and parallel to the cutter axis to lead the point of operation of the cutter in convex curves about the vertical axis of the heel and the longitudinal axis of the shank respectively.

50 78. In a machine for breasting Louis heels, 45 a rotary cutter having a formed cutting edge each extremity of which swings around into approximate perpendicularity to the cutter axis, and a work support constructed and arranged to present a shoe with its sole toward the cutter and to move translationally past the cutter, and guiding means against which the support and shoe 55 can be swung and held during the translation, comprising forms constructed and arranged to oscillate them toward and from the cutter perpendicular to its axis, whereby 60 the upper part of the heel breast is convexed, and to oscillate them also toward and

from the cutter parallel to its axis, whereby the end of the cutting edge lying along the shank convexes the upper forward end of the heel breast to correspond with the shank.

79. In a machine for breasting Louis 70 heels, a rotary cutter, a work support constructed and arranged to present the angle between the heel breast and shank to the cutter and to relatively traverse the shoe and the cutter in a direction laterally of the 75 shoe, with provision for universal movement in a plane perpendicular to the direction of traverse, comprising cam guides formed correspondingly to the curves desired at the junction of the heel breast and shank.

80. In a machine for breasting Louis heels, a rotary cutter, a shoe support arranged to carry the shoe over the cutter while maintaining its orientation substantially unchanged, a rod on one end of which the shoe support is mounted, and the other end of which is moved in a direction longitudinally of the rod to move the shoe as stated, and means comprising a cam for 90 moving the shoe in a direction transverse to the rod to shape the junction of the heel breast and shank.

81. In a machine for breasting Louis 95 heels, a rotary cutter, a shoe support arranged for relative traverse in a direction horizontally transverse to the shoe, and means for moving the effective operating point of contact of the cutter and shoe along the surface of the cutter periphery as 100 the said point of contact moves from one side of the shoe to the other, in such manner that the junction of the heel breast and shank is curved.

82. In a machine for breasting Louis 105 heels, a rotary cutter and a shoe support arranged for relative traverse in a direction horizontally transverse to the shoe, and means for controlling the relative movement 110 to compound with the relative movement of approach and separation between the cutter and the central point at the junction of the shank and heel breast, normally produced by a rectilinear relative traverse, a component of successive relative separation and approach whereby the said central point and cutter move relatively in a curve to make convex the junction of the shank and heel breast.

83. In a machine for breasting Louis 120 heels, a rotary cutter and a shoe support arranged for relative movement to carry the cutter across the breast of the heel from side to side, and means comprising a cam-guide for determining a relative swinging movement between the heel and the cutter as the cutter moves across a heel breast to curve the heel breast near its junction with the shank.

84. In a machine for breasting Louis 130 heels, a rotary cutter having a formed cut-

ting edge one end of which swings around into approximate perpendicularity to the cutter axis, a shoe support arranged for relative traverse in a direction horizontally transverse to the shoe, and means for moving the effective operating point of contact of the cutter and shoe across the surface of revolution of the cutter as the said point of contact moves from one side of the shoe to the other in such manner that the junction of the heel breast and shank is curved.

85. In a heel breasting machine, a shoe support, rotary breasting means, a main shaft, speed increasing means from the main shaft to the rotary means, speed reducing mechanism from the main shaft, and connections from said mechanism to the shoe support to effect relative movement of the breasting means and the shoe support to effect the breasting operation.

86. In a heel breasting machine, a shoe support, rotary breasting means, a main shaft, belt means from the main shaft to the rotary means, speed reducing mechanism from the main shaft, and connections from said mechanism to effect relative movement of the shoe support and the breasting means to cause the base portion of the heel to be trimmed to correspond to the transverse curvature of the shank.

87. In a machine for breasting heels, a rotary cutter, shoe holding means mounted for movement in two planes at right angles to each other, and means for determining movement of the shoe in each plane relatively to the cutter to cause the base portion and the breast portion of the heel to be differently curved transversely.

88. In a machine for breasting heels, a rotary cutter, shoe positioning means mounted for movement in two planes at right angles to each other, power means for effecting movement of the positioning means in one plane relatively to the cutter, and means acting as an incident to such movement to determine relative movement of the cutter and positioning means in the other plane.

89. In a machine for breasting heels, a rotary cutter, shoe positioning means mounted for swinging movements in planes at right angles to each other, power means for moving the shoe positioning means in one of said planes, and means acting in response to such movement to move the positioning means in the other plane.

90. In a machine for breasting Louis heels, a rotary cutter, shoe positioning means mounted for swinging movements in planes at right angles to each other, power means for moving the shoe positioning means in one of said planes and means acting as an incident to said power effected movement to determine the transverse curvature of the base portion of the heel breast.

91. In a heel breasting machine, a shoe

support, rotary breasting means, a main shaft, belt means from the main shaft to the rotary means, speed reducing mechanism from the main shaft, and connections from said mechanism to effect movement of the shoe support relatively to the breasting means to cause the heel of the shoe to be breasted.

92. In a heel breasting machine, a shoe support, rotary breasting means constructed and arranged to be driven at high speed, and power connections for causing relative movement of the breasting means and the shoe support to effect the breasting operation at lower speed.

93. In a machine of the class described, the combination of means for locating a shoe and its attached heel in predetermined position, a rotary cutter, means for moving the shoe so positioned in a direction transverse to the cutter axis, means for arresting movement of the shoe when the center of the heel breast is in line with the axis of the cutter, and means enabling the shoe to be moved substantially in its longitudinal median plane to cause the cutter to form a scallop in the breast face of the heel.

94. In a machine of the class described, the combination of means for convexing the shank portion of a heel and for concaving the portion of the breast of the heel adjacent to its tread face, and a heel support between which and said means there is provision for relative movement to cause said means to operate upon the heel.

95. In a machine of the class described, a form cutter shaped to produce a longitudinal curvature of the breast of a Louis heel corresponding to the shape of the cutter, a shoe support, and means for relatively moving the cutter and support to cause the cutter to shape the base portion of the heel flush with the transverse curvature of the shank.

96. In a machine of the class described, a form cutter shaped to produce a longitudinal curvature of the breast of a Louis heel corresponding to the shape of the cutter, a shoe support, and means for relatively moving the cutter and support to cause the cutter to produce on a portion only of the heel breast a convex shape blending with the transverse curvature of the shank.

97. In a machine of the class described, a form cutter shaped to produce a longitudinal curvature of the breast of a Louis heel corresponding to the shape of the cutter, a shoe support, and means for relatively moving the cutter and support to cause the cutter to shape the breast longitudinally in accordance with the shape of the cutter to trim the base portion of the heel flush with the shank and to give a convex formation to another portion of the heel breast.

98. In a machine of the class described, the combination of a plurality of rotary cutters on horizontal axes located in different positions spaced vertically with respect to each other, a shoe support, and means for moving the support vertically first into position for the operation of one cutter upon the shoe and then into position for operation of the other cutter upon the shoe.

99. In a machine of the class described, the combination of a plurality of cutters located in different positions spaced vertically with respect to each other, a shoe support, and means for effecting relative vertical power movement between the cutters and the support first to position the shoe and cutter for operation of that cutter upon the shoe and then relatively to position the shoe and the other cutter for the operation of the other cutter upon the shoe.

100. In a machine of the class described, the combination of shoe positioning means, heel breasting means, heel scalloping means, means for relatively operating the positioning means and the breasting means to breast the heel, and means for relatively operating the positioning means and the scalloping means to scallop the heel.

101. A machine of the class described having, in combination, a shoe support for locating a shoe in predetermined position, a rotary cutter, means for effecting relative movement between the support and cutter to cause relative traverse of the heel and cutter in a direction from side to side of the heel, and means acting during said relative movement for causing relative movement of the heel and cutter about an axis.

102. In a machine of the class described, the combination of a rotary form cutter having cutting edges which correspond to

the longitudinal curvature of a Louis heel breast, means for presenting a shoe to the cutter, and means for effecting relative movement between the cutter and presenting means to cause the cutter to trim the base portion of the heel from side to side flush with the curved shank of the shoe.

103. In a machine of the class described, the combination of a pair of rotary cutters on horizontal axes separated from each other in a direction perpendicular to their axes, a shoe support for presenting a shoe to the cutters in turn, and means for effecting relative movement between the support and cutters perpendicular to said axes from a position suitable for operation of one of the cutters into position for operation of the other cutter upon the shoe.

104. In a machine of the class described, the combination of a pair of power driven tools for operating on a shoe bottom, said tools being mounted on separate parallel axes, said axes being horizontally arranged, a shoe support upon which the shoe is presented to the tools in turn, and power means for effecting relative vertical movement between the support and tools from a position suitable for the operation of one of the tools into position for operation of the other tool upon the shoe.

105. In a machine of the class described, the combination of continuously operated breasting means, continuously operated scalloping means, shoe positioning means, and means for relatively moving the positioning means and the breasting and scalloping means to effect operation of the breasting means and the scalloping means upon the heel in succession.

In testimony whereof I have signed my name to this specification.

LOUIS A. CASGRAIN.
